TOWEL DISPENSING CABINET

John B. Engel, Green Bay, Wis., assignor to Bay West Paper Company, Green Bay, Wis.

Filed Nov. 20, 1970, Ser. No. 26,083

Term of patent 14 years

Int. Cl. D31; D6—04

U.S. Cl. D52—2

Fig. 1

Fig. 3

Fig. 2

FIG. 1 is a front elevational view of the towel dispensing cabinet showing my new design.

FIG. 2 is a top plan view thereof.

FIG. 3 is a right side elevational view, the left side being a mirror image.

FIG. 4 is a bottom plan view thereof.

The rear of the towel dispensing cabinet not shown is conventional.

I claim:

The ornamental design for a towel dispensing cabinet, as shown and described.
